UNITED STATES PATENT OFFICE.

JOHN HORATIO FENNEY, OF HANDSWORTH, NEAR BIRMINGHAM, ENGLAND.

BALL-CASTER.

No. 903,850.

Specification of Letters Patent.

Patented Nov. 17, 1908.

Application filed June 22, 1906, Serial No. 322,826. Renewed September 17, 1908. Serial No. 453,506.

To all whom it may concern:

Be it known that I, JOHN HORATIO FENNEY, a subject of the King of Great Britain, residing at 52 Montague road, Handsworth, 5 near Birmingham, in the county of Stafford, England, traveler, have invented certain new and useful Improvements in Ball-Casters, of which the following is a specification.

My invention relates to improvements in 10 ball casters and has for its objects to construct or provide such in a simpler and more efficient manner than heretofore, from which all dust is excluded thereby preventing the present liability to become clogged or de- 15 ranged.

To this end my invention consists in mounting the main ball in a ball race or bearing at the foot of the main cylinder, a rubber or other resilient diaphragm immediately 20 below the main ball, and which prevents the ingress of dust. Immediately above the main ball is mounted another ball which takes the vertical thrust, this ball being located in a recess in a diaphragm. The main 25 shell may be inclosed in an outer shell of thin metal which holds the various parts together.

In order that my invention may be clearly understood and more readily carried into practice, I have appended hereunto a sheet of 30 drawings illustrating the same, wherein:—

Figure 1. is an outside elevation of a ball 35 caster, according to one form of my invention. Fig. 2. is a sectional elevation of the same. Fig. 3. is a transverse sectional view 40 at 1—2, in Fig. 2. Fig. 4. is an outside elevation of a modification of my ball caster. Fig. 5. shows the same form of the invention in sectional elevation, and Fig. 6. is an inverted plan of the caster.

In constructing a ball caster according to 45 the form of my invention illustrated at Figs. 1—3, I take a cylindrical piece C preferably of iron or steel. Within this cylinder C is provided a diaphragm D, beneath which is located a ball T which receives the thrust from the main ball B situated immediately 50 below it. At the bottom of the said cylinder C and within same is provided a ring E carrying a plurality of balls e, four being

in contact with the aforementioned ball B. At the bottom of the cylinder C, I provide a rubber or equivalent flexible diaphragm R, having a central hole through which the ball B projects. Around the aforesaid cylinder C, I provide an outer shell, S, preferably of brass, which is flanged inwardly at its base, this flange, s, pinching the diaphragm R at its outer edges between the bottoms of the inner cylinder and the ring 60 carrying antifriction balls, firmly holding such diaphragm R against the cylinder C, and thereby securing it firmly in position. The shell S, cylinder C and diaphragm D are preferably secured together by screws d 65 as illustrated. It will be seen that in this form of caster, the ball B bears upon the floor and rotates when the caster is moved, the balls e facilitating such movement, while the ball T receives the vertical thrust and 70 enables the ball B to move with a minimum of friction. The flexible diaphragm R, exerts a yielding and hugging pressure on the main ball and securely closes the bottom of the caster, excluding all dust, while the dia- 75 phragm D similarly seals the top.

In the form of caster illustrated at Figs. 4—6, the main cylinder F is forged and integral with the upper diaphragm f in which a similar thrust ball T is located, the main 80 ball B being immediately below the aforesaid ball T. At the bottom of the cylinder F a ring E which may be separate as shown, or integral with the cylinder, is provided within which balls e are located, these balls 85 e being in contact with the ball B. At the bottom a similar flexible diaphragm R is provided, the whole being held together by an outer shell S¹ flanged at s¹ in the manner explained for the previous form of the 90 invention.

What I claim then is:—

In a ball caster, the combination of an outer cylindrical shell having a flanged in portion; an inner cylindrical piece, a main ball, a set of antifriction balls holding said main ball in position and a ring around said main ball below its center and carrying said antifriction balls, an upper diaphragm, an upper thrust ball in the said upper dia- 100

phragm, and a flexible perforated dia-
phragm below the main ball and closing the
bottom of the caster, the said diaphragm be-
ing carried between the lower flanged in por-
5 tion of the outer shell and the lower portion
of the inner cylinder, the whole forming an
anti-friction, noiseless and dust proof caster.

In testimony whereof, I have signed my
name to this specification in the presence of
two subscribing witnesses.

JOHN HORATIO FENNEY.
